UNITED STATES PATENT OFFICE.

CHARLES H. BOECK, OF JACKSON, MICHIGAN, ASSIGNOR TO THE NOVELTY MANUFACTURING COMPANY, OF SAME PLACE.

DESIGN FOR AN OIL-STOVE.

SPECIFICATION forming part of Design No. 23,931, dated January 1, 1895.

Application filed November 19, 1894. Serial No. 529,323. Term of patent 7 years.

To all whom it may concern:

Be it known that I, CHARLES H. BOECK, a citizen of the United States, residing at Jackson, in the county of Jackson and State of Michigan, have invented and produced a new and original Design for an Oil-Stove, of which the following is a specification, reference being had therein to the accompanying drawings, in which—

- 10 Figure 1 is a front elevation, and Fig. 2 is an end elevation.
A are side standards.
B is the top, having bevel edges.
B' is a flat diaphragm or plate, extending 15 between the standards about midway the height thereof. Below this diaphragm is a substantially rectangular tank, C, having rounded front and rear faces D, as plainly shown in Fig. 2. From near the ends of this 20 tank, project upwardly the cylindrical wick tubes E, terminating in flaring rings F, and capped by conical frustum shaped chimneys

G. Below the tank, and in line with the wick tubes E depend the cylindrical tubes H of smaller diameter than the wick tubes. Between these tubes H is a plate or edging I, having its lower edge gracefully curved as shown.

K is a beading on the tubes H and plate I, having the appearance of a continuous band 30 across the faces thereof.

The leading feature of the design is the configuration of the tank and its connected parts supported in the frame as shown in the drawings.

What I claim as my invention is—

The design for an oil stove, substantially as shown and described.

In testimony whereof I affix my signature in presence of two witnesses.

CHARLES H. BOECK.
